(57) **CLAIM**

The ornamental design for a foldable charger, as shown and described.

DESCRIPTION

FIG. 1 is a top, front, and left perspective view of a foldable charger showing our new design unfolded, in a first configuration;

FIG. 2 is a top, rear and right perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top, left, and front perspective view thereof, shown in a first condition of use, charging a mobile phone and a set of earphones;

FIG. 10 a top, left perspective view of the foldable charger, shown partially folded, in a second configuration;

FIG. 11 is top, left perspective view thereof, shown in a second condition of use, charging a mobile phone;

FIG. 12 is a top, front and left perspective view of the foldable charger, shown fully folded, in a third configuration; and,

FIG. 13 is a top, front and left perspective view thereof, shown in a third condition of use, charging a mobile phone. The broken lines on the foldable charger depict portions of the foldable charger that form no part of the claimed design. In FIGS. 9, 11 and 13, the broken lines showing a mobile phone and a set of earphones depict environmental subject matter only, and form no part of the claimed design.

1 Claim, 13 Drawing Sheets
